UNITED STATES PATENT OFFICE.

HAMILTON C. STUART, OF ST. JOHNSBURY, VERMONT.

GAS-BURNER.

1,218,012.

Specification of Letters Patent.

Patented Mar. 6, 1917.

Application filed September 29, 1916. Serial No. 122,898.

To all whom it may concern:

Be it known that J. HAMILTON C. STUART, a citizen of the United States, residing at St. Johnsbury, in the county of Caledonia 5 and State of Vermont, have invented certain new and useful Improvements in Gas-Burners, of which the following is a specification.

This invention relates to an improved fire 10 kindler and the principal object of the invention is to provide an improved fire kindler of the gas fuel type, an improved type of burner being provided so constructed that ashes cannot gather upon the upper 15 end thereof to clog the gas outlet opening.

Another object of the invention is to so construct this burner that it will cover a relatively great amount of space with respect to the grate of the stove thus permitting the coal or other fuel in the fire box 20 of the stove to be quickly ignited.

Another object of the invention is to so construct this kindler that it will not interfere with the removal of ashes from the 25 ash pit.

This invention is illustrated in the accompanying drawings, wherein:—

Figure 1 is a view showing the fire box 30 of a stove in section with the fire kindler in elevation.

Fig. 2 is an enlarged view in side elevation of the burner.

Fig. 3 is a vertical sectional view through the burner.

Fig. 4 is a vertical sectional view through the burner taken at right angles to the showing in Fig. 3.

The stove indicated in general by the numeral 10 is provided with the usual fire 40 box 11 which fire box has the grate 12 and positioned above the ash pit 13. The pipe 14 enters the ash pit through one wall thereof and is provided with a valve 15 positioned outside the stove so that the gas can 45 be turned on. The burner 16 which is connected with the nipple 17 of the pipe 14 is provided with a base 18 having openings 19 formed therein to permit air to pass into the burner and to further permit fine dust 50 entering the burner to pass out through the

bottom thereof. The gas passing out through the tip 20 mixes with the air and therefore this burner will burn a blue flame. The upper portion of this burner 16 is enlarged to provide a flaring head 21 having 55 a tapered upper edge portion in which there is provided outlet openings 22 through which the mixed air and gas will pass. This flame which will be very hot will pass up through the grate bars and will engage the 60 coal or other fuel positioned in the fire box thus igniting the fuel therein and starting the fire. After the fire is started, the valve 15 can be turned to cut off the supply of gas. Ashes falling through the grate will strike 65 the sloping upper portion of this burner and will slide off and down into the ash pit thus preventing the burner from becoming clogged and making it necessary to remove the burner for cleaning. Any fine dust 70 which might sift through the openings 22 will pass out through the air inlet openings 19 or if it does remain in the base of the burner 16, it will be so positioned that it 75 will not interfere with the effective operation of the burner.

It will thus be seen that there has been provided a very effective fire kindler of the gas operating type.

What is claimed is:—

A stove including a fire box having a grate, a gas supply pipe entering the stove beneath the grate of the fire box and terminating in an upstanding nipple, and a burner mounted upon the nipple and including a tubular body having a bottom provided with a nipple receiving opening and air inlet openings positioned about the nipple receiving opening, the upper portion of the tubular body of the burner being formed 85 into a flared head terminating in a transversely tapered upper portion having outlet openings at the upper edge and along the sloping sides of the head.

In testimony whereof I affix my signature 90 in presence of two witnesses.

HAMILTON C. STUART.
